UNITED STATES PATENT OFFICE.

GEORGE P. CRAGIN, OF SPOKANE, WASHINGTON.

SHIRT AND CUFF THEREFOR.

Application filed February 9, 1920. Serial No. 357,460.

To all whom it may concern:

Be it known that I, GEORGE P. CRAGIN, a citizen of the United States, and a resident of Spokane, in the county of Spokane and 5 State of Washington, have invented certain new and useful Improvements in Shirts and Cuffs Therefor, of which the following is a specification.

My invention, while it relates in general 10 to improvements in soft shirts, is particularly applicable to the wristband of the shirt-sleeve and the detachable cuffs utilized in connection therewith. The cuff of the invention is of the reversible, soft, folded type, 15 adapted as a sport cuff usually worn with shirts made of flannel or similar material for outing purposes. The novel features and combinations and arrangements of parts of the invention may also be embodied in 20 shirts and cuffs especially designed for use with work or semi-business shirts.

By the combination and arrangement of 25 parts of my invention the straight edge effect of the attached cuff is attained, which insures a neat and well-groomed appearance 30 for the wearer of the detachable cuff herein referred to; the cuff may be attached and detached with facility; and when desired, the cuff may be reversed and yet present 35 the same finished aspect as when initially worn, before reversing.

The invention consists in certain novel 35 features of construction of the cuff, and of the wristband of the sleeve of a shirt, and in the novel combination and arrangement 40 of these parts as will hereinafter be more specifically pointed out.

In the accompanying drawings:—

Figure 1 is a perspective view of a shirt 45 sleeve and cuff embodying my invention, in position for wear, but with a portion of the outer fold of the cuff unbuttoned and turned out for convenience of illustration.

Figure 2 is a side elevation of a portion of 50 a sleeve with cuff attached, illustrating the outside of the left sleeve, and showing interior parts in dotted lines.

Figure 3 is an enlarged, detail sectional 55 view at line 3—3 of Figure 2, showing the relation of parts to the sleeve button.

Figure 4 is a perspective view of the lower 60 portion of a sleeve embodying my invention.

Figure 5 is a perspective view of a de- 65 tached cuff, according to my invention, in-

dicating the manner of folding the cuff upon itself.

Figure 6 is an enlarged, detail sectional view illustrating the manner of attaching the reversible button hole tab to the cuff. 60

The sleeve 10, which may be of soft material, is provided with a placket 11 as usual, and this placket or fly, at its adjoining edges is provided with side strips 12 and 13, 65 stitched along the edges of the placket, and terminating at their lower ends on a line with the upper edge of the wristband 14 of the sleeve. It will be noted however, in Figures 2 and 4 that the placket edges, or side strips 12 and 13, project beyond the 70 ends of the wristband 14, in order that when the wristband is folded and buttoned, an angular space is provided for a purpose to be described.

The wristband is attached to the end of 75 the sleeve by inserting the sleeve edge in between plies of the wristband and stitching, as at 15 in Figure 4, to secure the sleeve and band together. At one end the wristband is provided with the usual button hole 16 80 for the sleeve button B, while at its opposite end, the wristband is provided with a special attaching tab 17 with one end inserted in between and stitched to the plies of the wristband. The free end of the tab is fashioned 85 with a button hole 18, and by reference to the sectional detail view of Figure 3 it will be seen that the head of the sleeve button B is first passed through this hole 18, the tab is then turned in, and the button hole 16 of the 90 wristband is passed over the button B to secure the wristband about the wrist.

The wristband is fashioned of two or more plies or layers of material, and the stitches 95 pass through these plies and through the interposed material of the sleeve, to insure a strong and durable joint between the parts with a comparatively smooth and even fastening.

In dotted lines Figure 2, and in full lines 100 Figure 4 I have illustrated the wristband with a maximum width at its central folding line, and it will be noted that the band tapers to a comparatively narrower width toward its ends. 105

This formation of the wristband, as seen in Figure 2 provides a comparatively long folded edge at the front of the band, while the free ends of the band are utilized for the button hole 16 and button tab 17 of 110

the wristband. As seen in Figure 2, this comparatively long edge of the wristband extends a considerable distance down into the attached cuff 20, which is secured to the 5 sleeve button B as will be described, and it will be apparent that this long folded edge of the band provides a support by close contact with the cuff, that will prevent the cuff swinging on the button B 10 as a center. In this manner the cuff is supported on or fastened to the button B, and by the long edge of the band the cuff is maintained in proper position with relation to the sleeve and also prevented from 15 hanging loosely over the hand of the wearer.

This added width at the point of foldage of the band also facilitates the convenient positioning of the cuff by providing a guide for the latter as it is being slipped over 20 the wristband, and prevents interference by folds of the cuff because of the facility with which the point of the band at its free folded end may be slipped into the cuff.

23 The cuff 20 is designed to fold along a longitudinal line at approximately its center to provide an outer or exposed fold 21 and an inner, invisible fold 22, and it will be apparent that the cuff may be reversed for 28 use by folding a second time in manner opposite to the first fold.

Before folding the cuff is of approximately rectangular shape with a straight edge 23 to the outer fold and an intermediate 35 straight portion 24 and cut-away ends 25 to the edge of the inner fold 22. These cut-away or tapering edges 25 of the inner fold, when the cuff is folded as indicated for use, provide an open space between the 40 corners of the outer fold 21 to accommodate the fastening means by which the cuff is secured to the button B, thus reducing the thickness of the cuff where it is buttoned or secured to the sleeve button, as indicated 45 in Figure 3. By this means a cumbersome appearance of the cuff is avoided, material in the make-up of the cuff is saved, and facility and convenience are assured in fastening or unfastening the cuff to the 50 button B.

Near its free ends the cuff is fashioned with holes 26 in the inner fold, which register, and are adapted to be passed over the cuff button L, and the outer fold 21 of the cuff is provided with complementary 55 holes 27, to register and receive the cuff button L as shown in Figures 1 and 2.

The outer fold 21 of the cuff is used for 60 attachment to the wristband by means of the sleeve button B, and for this purpose the outer fold is provided near one edge with a hole 28, which, regardless of whether the obverse or reverse side of the cuff is being used, is always at the outside of the cuff as worn. In addition to this button

hole 28, an invisible fastening means for the cuff is provided for securing it to button B by the use of a tab 29 with its hole 30.

As best seen in Figure 6, this tab, which projects laterally from the inner fold of 70 the cuff at the end opposite to the end having the button hole 28, has its stationary end secured between plies of the cuff, as by 75 stitches, which extend both longitudinally and transversely of the tab and through the tab and the enclosing plies of the cuff. At 80 the cuff is slotted or provided with a slot which extends through all of the plies of the cuff and opens at both sides of the fold 21. The free portion of the tab projects 85 from its pocket (in which it is secured in the cuff) and it will be apparent that the free end of the tab may be passed through the slot to project at either side of the cuff-fold 21 so that the tab will be in position 90 for buttoning to the button B when the reverse side of the cuff is being used as well as when the obverse side is being used. The free end of the tab will of course always be positioned at the inner side of the fold 21 and will be passed through that portion of slot 31 at the inner ply of the outer fold 21.

After the wristband has been buttoned and the cuff slipped over the band, the free 95 end of the tab 29 is turned in and buttoned over the button B, and then the button hole 28 of the outer fold is slipped over the head of the button B to provide a neat appearing fastening means.

To reverse the cuff it is folded backwardly on its original line of foldage, then the tab 29, as in Figure 6 is drawn entirely through the slot 31 to the upper side of the cuff with its free end projecting beyond the 105 edge of the cuff, and the cuff is ready for use.

Whether the obverse or the reverse side of the cuff is being used the inner fold 22 is 110 always next to the wrist of the wearer, and the outer fold 21 is always exposed with its button hole 28 on the outside. That portion of the slot 31 at the inner side of the exposed face of the cuff always appears as a 115 blank and forms part of the smooth exposed portion of the cuff.

The utility of the angular notches formed at the adjoining angularly disposed ends of the side strips 12, 13 and the free ends of the wrist band will be apparent, as the space 120 formed by these notches is occupied by the overlapping tabs 17 and 29, the button-fastening device is hidden within this space, and the straight edge effect, as indicated in Figure 2 is assured to enhance the appearance 125 of the junction of the sleeve and cuff.

Various types of sleeve buttons and cuff buttons may be used, and as before stated different styles of shirts and complementary cuffs are readily adaptable for my invention.

Having thus fully described my invention, what I claim as new and desire to secure by Letters Patent is:—

1. A soft reversible cuff adapted to form an inner and an outer fold, said inner fold having its corners cut away and provided with cuff-button-holes, said outer fold having complementary button holes and a sleeve-button hole at one end, and said outer fold having at its opposite end a slot and a sleeve-button-hole tab adapted for use with said sleeve-button-hole at selective sides of the outer fold.

2. The combination with a sleeve having a wristband and angular notches at the junction of the wristband and sleeve forming a space, of a soft reversible cuff having inner and outer folds and complementary cuff-button-holes in said folds, said outer fold having a button hole at one end for attachment to a button in the wristband and said fold having a slot and an interchangeable button-hole tab at its other end adapted to occupy said space and for attachment to said button in the wristband.

GEORGE P. CRAGIN.
